UNITED STATES PATENT OFFICE.

CHARLES T. BLOOMER, OF NEWARK, NEW YORK.

PAPER RECEPTACLE.

1,081,264.

Specification of Letters Patent.

Patented Dec. 9, 1913.

Application filed January 17, 1912. Serial No. 671,636.

To all whom it may concern:

Be it known that I, CHARLES T. BLOOMER, a citizen of the United States, residing at Newark, in the county of Wayne and State 5 of New York, have invented a new and useful Paper Receptacle, of which the following is a specification.

This invention relates to paper receptacles.

One object of the invention is to provide 10 an article of this character in which a novel, simple, and readily constructed form of fastening means is provided for holding the cover locked relatively to the receptacle body and in such manner as to preclude all 15 danger of accidental opening, and which shall be easy of unsealing or releasing when the cover is to be opened.

A further object is to arrange the fastening means in such manner as to cause it to 20 perform the further function of a reinforce for the front wall of the receptacle, to brace the same against outward bulging and thus 25 danger of disengagement of the parts.

With the above and other objects in view, 30 as will appear as the nature of the invention is better understood, the same consists of the novel construction and arrangement of parts of a fastener for paper receptacles, as will be hereinafter fully described and claimed:

35 In the accompanying drawing forming a part of this specification and in which like characters of reference indicate corresponding parts: Figure 1 is a view in perspective of a paper receptacle equipped with the fastening device constituting the present invention, the cover being open. Fig. 2 is a fragmentary perspective detail view, showing the position of the parts of the locking device when the cover is closed and locked.

40 Fig. 3 is a transverse sectional view through the cover and front wall, showing the disposition of the parts of the fastener when in locked position. Fig. 4 is a fragmentary detail perspective view of a slightly modified form of the invention. Fig. 5 is a perspective detail view of the metallic fastener.

The box is of the usual or any preferred 45 type of either knock-down or nesting receptacle, and has its cover 1 provided with an ordinary tuck-flap 2 having a U-shaped slit 50 terminating at the base of the flap to provide a tab 3 that may be either semi-circular, as shown in Figs. 1 and 2, or approximately rectangular as shown at 4 in Fig. 4. The

tab is provided with a slot or aperture 5 at 55 its base or butt end that extends well into the cover and is designed to receive a metallic fastener or tongue 6, constructed preferably from a length of sheet tin, and which has its butt end secured to the inner face of 60 the front wall of the box by clenched prongs 7 so as to project above the upper edge of the front wall approximately in the plane of the said wall. The fastener is designed to project through the orifice when 65 the cover is closed, permitting the tuck-flap to lie close against the front wall 8 of the box, and is bent downward, thereby clamping the tab against the front wall, and at the same time exerting a downward pressure upon the adjacent wall of the orifice 70 and upon the upper edge of the front wall, thereby firmly securing the parts together. The tab performs a double function, namely that of a releasing member for the fastener, 75 and as a means of reinforcing the front wall of the box on each side of the fastener, so that any tendency of the wall to bulge outward, and thus endanger the stability of the fastening device, is precluded. As is 80 well known, boxes of this character are made of soft paste-board, which is highly absorbent, and should the front wall of the box become soaked with moisture, there will be a danger of the fastening device becoming 85 disconnected from the front wall, but by the provision of the tab, this will be obviated, as an extra thickness of material will be interposed between the fastening device and the front wall.

90 One of the salient or cardinal features of the present invention resides in the fact that the aperture 5 extends well into the cover, and the tab being struck from the flap provides an opening exposing the butt end of 95 the tongue, so that when the tip of the tongue is folded over the outer face of the front wall of the box with the tab, the inner end of the aperture 5 and the opening in the flap will permit access to the butt end 100 of the tongue, whereby the outer and inner portions of the tongue may be pinched together, so as to tightly clamp the tab and corresponding portion of the front wall together.

105 As to the fastener releaser, the value of this feature, it is thought, will be apparent, as it will be obvious that when the fastener

is bent to the position shown in Fig. 3, it will be an easy matter to release or unbend it by grasping the tab and forcing it upward, thus eliminating all danger of injury to the fingers of the operator, as from cutting, which frequently results in an attempt to unbend metallic fastening devices of this character.

In the use of the receptacle as an egg box, 10 as shown in Fig. 1, the ordinary filler is arranged in the box and the eggs placed in the compartments thereof. The lid is then closed, the tuck-flap being disposed against the inner face of the front wall of the box, 15 with the fastener 6 projected through the orifice 5. When the parts are thus positioned, the fastener is bent downward, thereby securely clamping the tab against the front wall, and effectively locking the cover 20 against danger of accidental opening.

While the improvements herein described are simple in character, it will be seen that they are thoroughly practical and efficient for the purpose designed, and that their 25 adaptation to the ordinary egg receptacle and paper pail in common use will not add appreciably to their cost of production.

What is claimed is:

A paper box embodying a cover having a tuck flap insertible within the opposite wall 30 of the box, said flap having a U-shaped slit, terminating at the base of the flap to provide a tab foldable over the outer face of the said wall, the tab having an aperture at its butt end extending well into the cover, 35 and a metallic tongue having its butt end clenched to the inner face of the said wall with its tip projecting upwardly and adapted to pass through the said aperture when the cover is closed, the tip of the tongue being bendable against the outer face of the said wall with the said tab, and that portion of the aperture extending into the cover and the opening provided in the flap by the tab, permitting direct access to the butt end 40 of the tongue, whereby the butt end and tip of the tongue may be clamped together.

In testimony that I claim the foregoing as my own, I have hereto affixed my signature in the presence of two witnesses.

CHARLES T. BLOOMER.
